WATER-LEVEL REGULATOR FOR STEAM-BOILERS.

1,401,892.

Specification of Letters Patent. Patented Dec. 27, 1921.

Application filed March 29, 1918. Serial No. 225,464.

To all whom it may concern:

Be it known that I, FRANCIS I. DU PONT, a citizen of the United States, residing at Wilmington, county of New Castle, and 5 State of Delaware, have invented a new and useful Improvement in Water-Level Regulators for Steam-Boilers, of which the following is a full, clear, and exact description, reference being had to the accompanying 10 drawings, which form a part of this specification.

My invention has for its object the automatic maintenance of a constant level of water in steam boilers. It is especially applicable to steam-driven automobiles, and in 15 such application has its greatest utility and value for the reason that it is particularly desirable in these vehicles that the driver's attention should be confined to as few duties 20 as possible.

The invention consists of means to pump water from a water reservoir or tank to the boiler, means adapted to return water from the boiler to the tank at a rate exceeding, or 25 at least not less than, the rate at which the water is pumped to the boiler, a heat interchanger arranged to transfer heat from the water flowing away from the boiler to the water flowing toward the boiler to prevent 30 the waste of heat that would otherwise occur, and means to prevent the conversion into steam of the water flowing from the boiler so as to insure the exchange of the maximum amount of heat before the return 35 of the water to the tank.

A preferred embodiment of the invention is shown in the accompanying drawing, the single figure of which is a diagrammatic view of the water tank and steam boiler and 40 of the pump, heat exchanger and other mechanism connected with the water tank and steam boiler and co-operating therewith and with each other. Only those parts and details are shown which are essential to a 45 full disclosure of the invention.

a represents the steam boiler; *b* the desired water level therein; *c* the water tank from which the boiler is kept supplied; and 50 *d* the feed pump, which takes water from the bottom of the water tank through pipe *o* and delivers it through the heat interchanger *e* into the boiler.

The plunger of the pump *d* is actuated by a connecting rod from one arm of a walk-

ing beam *f*, which in turn is actuated by any 55 means, but preferably by some mechanism geared to a shaft *f'* of the steam engine which is being supplied by the boiler *b*. The other arm of the walking beam *f* is connected to the plunger of what may be called a 60 measuring engine. This measuring engine comprises a cylinder *g* and a plunger *h*. The cylinder *g* has at least as great a capacity as, and preferably a slightly greater capacity than, the cylinder of feed pump *d*. It has 65 ports and a slide valve *i* which is operated by a rigid arm *j* on the end of the plunger itself. This arm *j* engages, just before the end of the inward stroke, with a shoulder *k* on the valve stem and shifts the valve *i* 70 to open communication between a pipe *m* (which leads from within the boiler at a point at which it is desired to maintain the water level) and the cylinder *g* of the measuring engine the arrangement being such 75 that the water or steam or water and steam are delivered to the measuring engine under boiler pressure so that the measuring engine also assists the engine in moving the walking beam *f* in one direction. Just before the 80 end of the outward stroke of the plunger *h* of the measuring engine, the rigid arm *j* engages a head *l* on the end of the valve stem and shifts the valve *i* to close communication between the pipe *m* and the cylinder *g* of 85 the measuring engine, at the same time opening communication between the cylinder *g* and the pipe *n* which leads to the heat interchanger *e*.

As long as the water level in the boiler *a* 90 is above the end of the pipe *m*, the cylinder *g*, being of greater capacity than the cylinder of the feed pump *d*, will take more water out of the boiler than the feed pump can deliver into it. When, however, the level 95 of the water in the boiler falls below the end of the pipe *m*, the latter will receive only steam, and the water level in the boiler will rise until equilibrium is established. The heat interchanger *e* is not a substitute for 100 the usual feed water heater operating by exhaust steam from the engine. Should an ordinary heater be used it must be introduced in the pipe *o* between the feed pump and the heat interchanger as indicated in dotted 105 lines, and may be connected in any desired manner to the exhaust of the engine. The purpose of the interchanger is to neutralize

what would otherwise be a waste of heat resulting from a continuous withdrawal of hot water and steam from the boiler.

The heat interchanger can be of any of 5 the well known forms, but that shown consists in a coil p for the feed water extending through a chamber in which is a series of diaphragms r , each perforated with a small hole, thus dividing the interchanger into a 10 series of superimposed chambers, the upper one of which contains the hottest water and transfers heat in the greatest degree to the coil through which the feed water passes. The other chambers grade downward in 15 temperature as the incoming feed water takes heat away from them.

By means of this interchanger the heat units in the stream of withdrawn water are 20 immediately transferred to the ingoing feed water and substantially no heat is lost.

The importance of this is at once recognized when the state of affairs in a steam automobile which is running down hill is considered. Here the feed pump (which is usually geared to the axle) is working and a 25 stream of water is being pumped into the boiler, but the engine is not using any steam. With the present day steam automobiles, the feed pump must be by-passed either by a 30 hand operated valve or by a device dependent on expansion of metals, which does not always work satisfactorily. If this is not done, the boiler becomes too full. My device not only renders it impossible for the 35 boiler to become too full, but prevents the loss of heat units due to pumping into the boiler water which, by reason of the fact that the engine is not delivering any exhaust steam, has not been heated.

40 If there were nothing to prevent, the water, as soon as delivered through the pipe n into the chambers of the interchanger e , would, owing to its high temperature, flash into steam and rush out into the tank c at atmospheric pressure. This would leave the 45 chambers of e full of steam at atmospheric pressure. Under these circumstances, very little of the heat due to the boiler pressure would be saved by the interchanger.

50 To obviate this I provide a differential valve s working in a chamber t connected by pipe y with the supply tank c , a lower chamber u connected by a pipe z with the lower chamber of the heat exchanger and 55 an upper chamber v connected by a pipe w with the steam space of the boiler a . The live steam pressure acting through the pipe w tends to hold valve s down on its seat, thereby closing the outlet from the heat interchanger. However, the lower end of the 60 valve is larger in area than the end acted on by the live steam; and when the pressure in the interchanger rises sufficiently, it raises the valve, and water from the interchanger 65 escapes into the chamber c . Thus, valve s

acts as a regulating check valve, allowing exit of the water from the interchanger at a pressure which will vary with the boiler pressure, but will be lower in proportion as the area of the seat is larger than the area 70 of the plunger of the valve.

Having now fully described my invention, what I claim and protect by Letters Patent is:

1. In an apparatus for regulating the 75 water level in a steam boiler, the combination with a water supply tank, of a water line extending from the tank to the boiler, means in said line between the tank and boiler to deliver water from the tank to the 80 boiler at a rate in excess of the rate at which the water is converted into steam in the boiler, a second line from the boiler to the tank to which passes the water from the 85 boiler which rises above a predetermined level, means in the second line between the tank and boiler for withdrawing a predetermined volume of fluid from the boiler in a given time and transferring it to the tank, and a heat interchanger in said lines to 90 transfer heat from the outgoing fluid from the boiler to the ingoing water without intermingling in the interchanger.

2. In an apparatus for regulating the 95 water level in a steam boiler, the combination with a feed pump to continuously deliver water to the boiler at a constant rate, and an overflow pipe connected with the boiler at the desired water level, of a measuring engine connected with the last named 100 pipe and comprising a cylinder, a piston and mechanically actuated control valves, and valve actuating mechanism arranged to control the inlet to and outlet from the engine cylinder to cause the piston to be acted 105 upon by the boiler pressure during the passage of fluid to the cylinder and to cut off said pressure during the passage of fluid from the cylinder.

3. In an apparatus for regulating the 110 water level in a steam boiler, the combination with a feed pump to continuously deliver water to the boiler at a constant rate and a valve controlled measuring engine arranged 115 to be acted upon by the boiler pressure in one direction only and permit a predetermined quantity of fluid to pass from the boiler and acting to withdraw from the boiler water rising above a predetermined level, means for actuating the control valves, 120 and actuating connections between the measuring engine and the feed pump to utilize the power of the engine in operating the feed pump.

4. In an apparatus for regulating the 125 water level in a steam boiler, in combination, a boiler, a water supply tank, means to deliver water from the supply tank to the boiler, and means of at least as great a capacity as the water-delivery-means to re- 130

turn water from the boiler to the tank, the last named means being rendered inoperative to withdraw water upon the recession of the water in the boiler to a predetermined 5 level.

5. In an apparatus for regulating the water level in a steam generator, a water inlet line leading from a supply to the generator, means to continuously deliver water from 10 the supply to the generator at a predetermined rate through said line, a second line separate from the inlet line leading from the generator to the supply, means in the second line to withdraw from the generator 15 through said second line any excess water fed thereto, and a double surface heat interchanger connected to the two lines arranged to deliver the heat of the outgoing fluid to the ingoing water.

20 6. In an apparatus for regulating the water level in a steam boiler, in combination, a boiler, a water supply tank, means to deliver water from the tank to the boiler and to return from the boiler to the tank water supplied to the boiler in excess of the amount 25 of water converted into steam, and a heat interchanger adapted to transfer heat from the water returning from the boiler to the water being delivered to the boiler.

30 7. In an apparatus for regulating the water level in a steam boiler, in combination, a boiler, a water supply tank, means to deliver water from the tank to the boiler and to withdraw water from the boiler, a heat 35 interchanger adapted to transfer heat from the water withdrawn from the boiler to the water being delivered thereto, and a yielding regulating contrivance adapted to restrain the escape of the return water from 40 the heat interchanger until the pressure in the interchanger reaches a predetermined pressure below boiler pressure.

45 8. In an apparatus for regulating the water level in a steam boiler, in combination, a boiler, a water supply tank, means to deliver water from the tank to the boiler and to return water from the boiler to the tank, a heat interchanger adapted to transfer heat from the water returning from the boiler 50 to the water being delivered to the boiler, and a yielding regulating contrivance adapted to restrain the flow of water from the heat interchanger to the tank until the pressure in the heat interchanger reaches a predetermined pressure below boiler pressure.

55 9. In an apparatus for regulating the water level in a steam boiler, in combination, a boiler, a water supply tank, a pipe connection between the tank and the boiler, a pump 60 interposed in said connection, a second pipe connection between the tank and the boiler, and a measuring engine in the second pipe connection having a capacity not less than that of the pump and tending to withdraw 65 water from the boiler at a rate not less than

that at which it is pumped to the boiler, the second pipe connection communicating with the interior of the boiler at a point corresponding to the desired level of water therein.

70 10. In an apparatus for regulating the water level in a steam boiler, in combination, a boiler, a water supply, a feed pump and feed pipe connection adapted to transfer water from the supply to the boiler at 75 a rate in excess of the rate at which the water is converted into steam in the boiler, an outflow pipe connection from the boiler at the desired water level, a measuring engine in the second pipe connection having a 80 capacity not less than that of the feed pump and tending to withdraw water from the boiler at a rate not less than that at which it is pumped to the boiler, and a heat interchanger, interposed in both pipe connections, adapted to transfer heat from the outgoing to the incoming water without the intermingling thereof.

85 11. In an apparatus for regulating the water level in a steam boiler, in combination, a boiler, a water supply tank, a pipe connection between the tank and the boiler, a pump interposed in said connection, a second pipe connection between the tank and the boiler at the desired water level, a 90 measuring engine in the second pipe connection having a capacity not less than that of the pump and tending to withdraw water from the boiler at a rate not less than that at which it is pumped to the boiler, and a heat 95 interchanger, interposed in both pipe connections, adapted to transfer heat from the outgoing to the incoming water.

100 12. In an apparatus for regulating the water level in a steam boiler, in combination, a boiler, a water supply tank, means to deliver water from the tank to the boiler and to withdraw water from the boiler, a connection at the desired water level through which the water is drawn, a heat interchanger adapted to transfer heat from the water withdrawn from the boiler to the water being delivered thereto, a yielding 105 regulating valve adapted to restrain the escape of water from the heat interchanger 110 and a connection from the steam space of the boiler to said valve whereby the latter is prevented from yielding to allow the water to escape from the interchanger until the pressure therein reaches a predetermined 115 degree below boiler pressure.

120 13. In an apparatus for regulating the water level in a steam boiler, in combination, a boiler, a water supply tank, means to deliver water from the tank to the boiler 125 and to return water from the boiler to the tank, a connection at the desired water level through which the water is drawn, a heat interchanger adapted to transfer heat from the water returning from the boiler to the 130

water being delivered to the boiler, a yielding regulating valve adapted to restrain the flow of water from the heat interchanger to the tank, and a connection from the steam space of the boiler to said valve whereby the latter is prevented from yielding to allow the water to flow to the tank until the pressure in the heat interchanger reaches a predetermined degree below boiler pressure.

14. In an apparatus for regulating the water level in a steam boiler, in combination, a boiler, a water supply tank, means to deliver water from the tank to the boiler and to withdraw water from the boiler, a heat interchanger adapted to transfer heat from the water withdrawn from the boiler to the water being delivered thereto, a pressure regulating valve in the outlet from the heat interchanger, said valve having differential pressure areas, the larger pressure area opposing the passage of water from the interchanger, and a steam pipe connection from the boiler to the smaller area of the valve, whereby the pressure in the heat interchanger is maintained above atmospheric pressure but below the boiler pressure and whereby the valve releases to allow the escape of water from the interchanger at a pressure below the boiler pressure determined by the difference between said pressure areas.

15. In an apparatus for regulating the water level in a steam boiler, in combination, a boiler, a water supply tank, means to deliver water from the tank to the boiler and to return water from the boiler to the tank, a heat interchanger adapted to transfer heat from the water returning from the boiler to the water being delivered to the boiler, a pressure regulating valve in the passage from the heat interchanger to the tank, said valve having differential pressure areas, the larger pressure area opposing the passage of water to the tank, and a steam pipe connection from the boiler to the smaller area of the valve, whereby the pressure in the heat interchanger is maintained above atmospheric pressure but below the boiler pressure and whereby the valve releases to allow the return of water to the tank at a pressure below the boiler pressure determined by the difference between said pressure areas.

16. In an apparatus for regulating the water level in a steam boiler, in combination, a boiler, a water supply, a feed pump and feed pipe connection adapted to transfer water from the supply to the boiler, an outflow pipe connection from the boiler at the desired water level, a measuring engine in the second pipe connection having a capacity not less than that of the feed pump and tending to withdraw water from the boiler at a rate not less than that at which it is pumped to the

boiler, a heat interchanger, interposed in both pipe connections, adapted to transfer heat from the outgoing to the incoming water, a steam pipe connected with the boiler, and a valve having a pressure face of relatively small area open to the pressure in said steam pipe and a pressure face of relatively large area open to the pressure of water in the pipe connection in which the heat interchanger is interposed and adapted to shut off the escape of water therefrom until the pressure therein approaches the boiler pressure to a degree dependent upon the difference in said pressure areas.

17. In an apparatus for regulating the water level in a steam boiler, in combination, a boiler, a water supply tank, a pipe connection between the tank and the boiler, a pump interposed in said connection, a second pipe connection between the tank and the boiler at the desired water level, a measuring engine in the second pipe connection having a capacity not less than that of the pump and tending to withdraw water from the boiler at a rate not less than that at which it is pumped to the boiler, a heat interchanger interposed in both pipe connections, a steam pipe connected with the boiler, and a valve having a pressure face of relatively small area open to the pressure in said steam pipe and a pressure face of relatively large area open to the pressure of water in that part of the second pipe connection between the heat interchanger and the tank and adapted to shut off the return flow of water therein until the pressure in the heat interchanger approaches the boiler pressure to a degree dependent upon the difference in said pressure areas.

18. Means for regulating the water level in a steam boiler comprising, in combination, a boiler, a water supply tank, a pipe connection between the tank and the boiler, a pump interposed in said connection, a second pipe connection between the tank and the boiler at the desired water level, a measuring engine in the second pipe connection having a capacity not less than that of the pump and tending to withdraw water from the boiler at a rate not less than that at which it is pumped to the boiler, and a heat interchanger adapted to transfer heat from the outgoing to the incoming water, said heat interchanger comprising a main chamber interposed in the second pipe connection, perforated horizontal partitions in said chamber dividing it into a series of superimposed communicating sub-chambers, and a coil extending through all the sub-chambers and interposed in the first pipe connection.

19. In a feed water system for steam generators, a water feed line, means for continuously delivering an excess supply of water to the generator through said line, an

- overflow line, means for removing the excess water from the generator through the overflow line, a heat interchanger between the generator and the water delivery means connected to both lines, the overflow line having means beyond the interchanger to resist the movement of fluid therethrough to condense the steam and transfer the heat from the outgoing fluid to the ingoing water.
20. In an apparatus for regulating the water level in a steam generator, in combination, a boiler, a water supply tank, means to deliver water from the supply tank to the boiler, means to withdraw excess water from the boiler, a heat interchanger adapted to transfer heat from the water withdrawn from the boiler to the water being delivered thereto, and a control device for controlling the flow of return water from the heat exchanger.
21. A water supply system for boilers comprising a water supply line for the boiler including a pump, a water discharge line leading from the boiler at the desired water level, a heat interchanger connected to the supply and discharge lines, a measuring engine between the heat interchanger and the boiler connected to the discharge line, said measuring engine having a cylinder and a piston therein, a valve for controlling the admission of fluid from the boiler to the cylinder and from the cylinder to the heat interchanger, connections between the valve and the piston for actuating the valve in timed relation to the piston, driving connections for the piston of the measuring engine, said valve being so timed with relation to the piston that the cylinder is open to the boiler pressure when the piston moves outward and closed to the boiler and open to the heat interchanger when the piston moves in the other direction, and actuating connections for the pump.
22. A water supply system for boilers comprising a water supply line for the boiler including a pump, a water discharge line leading from the boiler at the desired water level, a heat interchanger connected to the supply and discharge lines, a measuring engine between the heat interchanger and the boiler connected to the discharge line, other means beyond the interchanger for controlling the discharge of water therefrom, said measuring engine having a cylinder and a piston therein, a valve for controlling the admission of fluid from the boiler to the cylinder and from the cylinder to the heat interchanger, connections between the valve and the piston for actuating the valve in timed relation to the piston, driving connections for the piston of the measuring engine, said valve being so timed with relation to the piston that the cylinder is open to the boiler pressure when the piston moves outward and closed to the boiler and open to the heat interchanger when the piston moves in the other direction, and actuating connections for the pump.
23. A water supply system for boilers comprising a water supply line for the boiler including a pump, a water discharge line leading from the boiler at the desired water level, a heat interchanger connected to the supply and discharge lines, a measuring engine between the heat interchanger and the boiler connected to the discharge line, said measuring engine having a cylinder and a piston therein, a valve for controlling the admission of fluid from the boiler to the cylinder and from the cylinder to the heat interchanger, connections between the valve and the piston for actuating the valve in timed relation to the piston, driving connections for the piston of the measuring engine, said valve being so timed with relation to the piston that the cylinder is open to the boiler pressure when the piston moves outward and closed to the boiler and open to the heat interchanger when the piston moves in the other direction, and actuating connections for the pump.

In testimony of which invention, I have hereunto set my hand, at Philadelphia, Pa., on this 28th day of March, 1918.

FRANCIS I. DU PONT.
